UNITED STATES PATENT OFFICE.

JAMES T. BAILEY, OF PHENIXVILLE, PENNSYLVANIA.

CHRISTMAS-TREE HOLDER.

No. 873,402.

Specification of Letters Patent.

Patented Dec. 10, 1907.

Application filed February 25, 1907. Serial No. 369,144.

To all whom it may concern:

Be it known that I, JAMES T. BAILEY, a citizen of the United States, residing at Phenixville, in the county of Chester and State 5 of Pennsylvania, have invented certain new and useful Improvements in Christmas-Tree Holders, of which the following is a specification.

The present invention relates to an improved means for supporting Christmas trees or the like in an upright position, the object being to provide a simple and inexpensive device which can be readily applied to the base of the tree in such a manner as to hold 10 the same in the desired position, and which comprises few and simple parts which can be readily collapsed so as to occupy a minimum amount of space when not in use.

For a full description of the invention and 20 the merits thereof and also to acquire a knowledge of the details of construction of the means for effecting the result, reference is to be had to the following description and accompanying drawings, in which:

25 Figure 1 is a perspective view showing the application of the device; and, Fig. 2 is a top plan view of the tree holder.

Corresponding and like parts are referred to in the following description and indicated 30 in all the views of the drawings by the same reference characters.

In general, the support comprising the present invention embodies a spider carrying a plate upon which the base of the tree rests, 35 and a plurality of legs loosely connected to the arms of the spider, the upper extremities of the legs being provided with means for positively engaging the tree while the lower extremities are flared outwardly and rest 40 upon the floor or other support. In the specific construction of the spider, it will be observed that the same is formed of a series of cross bars intersecting at their middle portions to form the radial arms 1, each of the 45 arms 1 being provided at its extremity with a laterally extending pin 2 and the said pins being formed with elongated heads 3.

Resting upon the radial arms 1 at the point of their intersection is a plate 4 provided 50 with a central opening 5 through which any suitable fastening member may be driven into engagement with the lower end of the tree trunk. The supporting legs 6 are formed at intermediate points with elongated 55 openings or slots 7 receiving the pins 2 extending laterally from the extremities of the

radial arms 1. These slots 7 correspond to the elongated heads 3 of the pins 2 so that when the two are in alinement with each other, the legs 6 can be readily attached to 60 and detached from the spider. Inwardly extending prongs or points 8 are formed at the upper extremities of the legs 6, the said prongs being designed to embed themselves in the trunk of the tree in such a manner as 65 to hold the same rigidly in an upright position. In the preferred form of the invention, the legs 6 are curved longitudinally so that the lower portions thereof flare outwardly and the lower extremities of the legs 70 are formed with the shoes or basal flanges 9 which may be employed to secure the device to a suitable support, and which also serve to prevent injury to a carpet or other floor covering. 75

Having thus described the invention, what is claimed as new is:

1. In a device of the character described, the combination of a body portion upon which the tree trunk rests, the said body portion comprising a plurality of arms, and legs the intermediate portions of which have a detachable and interlocking connection with said arms while their upper portions are provided with means for engaging the tree trunk, one of the members being connected having a pin projecting therefrom provided with an elongated head while the opposite member is formed with an elongated opening corresponding to the head and receiving 85 the pin. 90

2. In a device of the character described, the combination of a spider formed with a plurality of arms, pins projecting laterally from the arms of the spider and formed with 95 elongated heads, and legs provided at intermediate points with elongated openings receiving the pins and corresponding with the elongated heads upon the same whereby a detachable and interlocking connection is 100 produced between the legs and arms, the upper portions of the legs being provided with means for engaging a tree trunk. 105

3. In a device of the character described, the combination of a spider comprising a series of cross bars intersecting at their middle portions whereby a plurality of radial arms is formed, a plate carried by the spider, lateral pins projecting from the arms of the spider and formed with elongated heads, and 110 a series of legs provided at intermediate points with elongated openings receiving the

pins and corresponding to the elongated heads upon the same whereby a detachable and interlocking connection is produced between the legs and arms, the upper extremities of the legs carrying inwardly extending prongs designed to embed themselves in a

In testimony whereof I affix my signature in presence of two witnesses.

JAMES T. BAILEY. [L. s.]
